(57) **CLAIM**

The ornamental design for a computer housing, as shown and described.

DESCRIPTION

FIG. 1 is a top-front perspective view of a computer housing showing my/our new design taken from a corner;

FIG. 2 is an enlarged front view thereof;

FIG. 3 is a side view thereof;

FIG. 4 is a top view thereof; and,

FIG. 5 is an enlarged detailed view of the front corner thereof.

The broken line showing of the two race track shaped regions on the front of the computer housing is for illustrative purposes only and forms no part of the claimed design. The unshown rear and bottom of the computer housing form no part of the claimed design.
